UNITED STATES PATENT OFFICE.

TREFFLÉ GUILBAULT, OF MONTREAL, CANADA, ASSIGNOR OF ONE-HALF
TO JOHN HENKEL, OF SAME PLACE.

BEDSTEAD.

SPECIFICATION forming part of Letters Patent No. 623,956, dated April 25, 1899.

Application filed May 26, 1898. Serial No. 681,851. (No model.)

To all whom it may concern:

Be it known that I, TREFFLÉ GUILBAULT, a subject of Her Majesty the Queen of Great Britain, residing in the city and district of 5 Montreal, Province of Quebec, Canada, have invented certain new and useful Improvements in Bedsteads, (for which I have obtained Letters Patent of the Dominion of Canada, dated April 13, 1898, and numbered 59,604;) and I do hereby declare the following 10 to be a clear, full, and exact description of the invention, such as will enable others skilled in the art to which it appertains to make and use the same.

15 My invention relates to improvements in bedsteads, and has particular relation to devices of this character which are capable of being folded to form a sofa.

20 The object of my invention is to provide a bedstead which is neat and attractive in appearance, durable in construction, and which can be operated with great ease.

25 To these and other ends my invention consists in the improved construction and combination of parts hereinafter fully described, and particularly pointed out in the claims.

In the drawings, in which similar letters of reference indicate similar parts in all of the views, Figure 1 is a top plan view of my im-

30 proved bedstead when intended for use as a bed. Fig. 2 is a side elevation of the same when used as a sofa. Fig. 3 is a cross-sectional view of the bedstead in the position shown in Fig. 2. Fig. 4 is a detail of the 35 hinged foot and catch.

A designates a bedstead having the bottom a , ends a' , and back a^2 . To the bottom a is connected the front a^3 by means of hinges located between the upper face of the bottom 40 and the lower edge of the front, the construction being such that the front may assume a vertical or horizontal position, as desired, the former being the position when used as a sofa, the latter when used as a bed. The upper edge of the front a^3 is provided with a series of hingedly-mounted feet a^4 , formed substantially as shown in Fig. 4, the foot portion a^5 serving as a fastening for the front into vertical position by being passed over

suitable pins a^6 , secured to the ends a' . When 50 the front is in the position shown in Fig. 1, the feet a^5 rest on the floor, and thus serve to support the front in position and give the front a slight upward inclination to prevent the falling out of children when placed therein. 55

A top a^7 is hingedly connected to the back a^2 and is provided with suitable folding supports a^8 , adapted to retain the top in vertical position when the device is used as a bed.

Springs a^9 are secured to the bottom a and 60 the inner face of the front a^3 in such manner as will allow of a ready folding in position when the bed is folded to form the sofa, as shown in Fig. 3. As a space is formed on the inside when the bed is folded, it is apparent that the bedding can be readily stored 65 therein.

A head-rest a^{10} is hingedly connected to one end and is adapted to fold over on the top when the bed is closed, as shown in Fig. 70 2, or to be turned over, as shown in Fig. 1, when used as a bed.

A pad a^{11} is adapted to rest on the top when used as a sofa. It will be obvious that this pad may be removable or fixed, as desirable. 75

The operation of the device is obvious, and it is not thought necessary to set it forth in detail.

Having thus described my invention, what I claim as new is—

1. A sofa-bedstead comprising a frame having a fixed bottom, ends and back; a front hingedly connected to said bottom; a top hingedly connected to said back; supports for said back when in a vertical position; and 85 pivotal supports for said front when in horizontal position.

2. A sofa-bedstead, comprising a frame having a fixed bottom, ends and back, and also having a front and top each hingedly connected thereto; supports for said top in its open position; and supports for said front when in open position said supports also serving to secure said front in its closed position. 90

3. A combined foot and catch, comprising 95 a hinge; and an extension secured to one of the leaves of said hinge, said extension having its end bent at an angle to form a hook

adapted to engage with a stop when in one position and also to serve as a supporting foot, substantially as described.

4. In a sofa-bedstead, the combination with a frame having a hinged front and top; folding supports for said top; and supports for said front; of a head-rest hingedly connected to said frame, adapted to fold over on said

top when in closed position, substantially as described.

In witness whereof I have hereunto set my hand in the presence of two witnesses.

TREFFLÉ GUILBAULT.
